CLAIM

The ornamental design for a soft boot for glass scraper, as shown and described.

DESCRIPTION

FIG. 1 is a top, front and left perspective view of a soft boot for glass scraper showing our new design;

FIG. 2 is a top plan view thereof;

FIG. 3 is a front view thereof;

FIG. 4 is right side view thereof, the Left side being a mirror image;

FIG. 5 is a rear view thereof; and,

FIG. 6 is a bottom plan view thereof.

The broken line showing of some portions in FIG. 1 is for illustrative purposes only and forms no part of the claimed design.
